DRINKING CUP

Robert L. Gray, Brooklyn, N. Y., and Louis V. Lucia, West Hartford, Conn., assignors to Lucup Corporation, Brooklyn, N. Y., a corporation of New York

Application February 18, 1936, Serial No. 64,506

8 Claims. (Cl. 229—1.5)

This invention relates to drinking cups, and more particularly to that type of cups which are made from paper or similar fibrous material.

These cups, as now commonly made, consist of a blank cut from a sheet of paper material which is folded upon itself to form a container or drinking cup.

Although there are paper drinking cups which have a folded, or beaded drinking edge, the most economical type of cups are simply produced from a thin sheet of paper and with a thin drinking edge which is comprised only of a single thickness of the paper material. It is well known that such cups with thin edges, although the most economical to produce, are unsafe in their use for drinking as their thin edges can cause injury by cutting the lips of the user.

An object of our invention, therefore, is to provide a drinking cup having a safe edge without necessitating the folding or beading of the said edge.

A further object is to provide a cup of the type described which has a drinking edge that is in effect, what might be properly termed, a "velvet" edge, inasmuch as the said edge has a pile consisting of loose fibers similar to velvet.

Our invention is illustrated in the accompanying drawing in which:

Figure 1 is a rear view of a flat type paper drinking cup comprising our invention.

Figure 2 is a side view in elevation showing the said cup in its extended form.

Figure 3 is a view, in perspective, of another type of a cup to which our invention may also be applied.

Figure 4 is a fragmentary view on an enlarged scale, in vertical section, illustrating our improved drinking edge for a paper cup.

Figure 5 is a similar view illustrating the common form of the drinking edge of said cups.

As illustrated in the drawing:

The numeral 5 denotes a drinking cup which is formed from a blank of paper that is folded over upon itself and secured together at its overlapping edges as at 6. The bottom of the said cup is formed by further folding the said blank as indicated at 7.

In a cup of the form shown in Figures 1 and 2, the front, or drinking side of the cup is curved, as at 8, and extends above the rear edge 9 so that when the cup is extended as in Figure 2, the edge 10 of the said extending portion 8 is used as the drinking edge.

In the form of a cup shown in Figure 3, the

drinking edge 11 of the cup is straight and any portion thereof may be used in drinking.

Our invention relates particularly to the provision of a soft drinking edge for a cup of the type commonly made from a paper blank and which has a thin edge of single thickness.

In other words, by our invention we provide for a cup of the character described, a drinking edge which is velvety, as that illustrated in Figure 4 of the drawing, instead of an edge which is sharp as at 12, as shown in Figure 5, and which is the form of an edge that all of the cups of said type now have for the reason that the said edge is thus formed by the present method of cutting the blanks from a stack of paper sheets with a cutting die upon a wooden block.

The objects of this invention may be accomplished in any suitable manner whereby the drinking edge of a cup will be formed in any desired shape and still leave the fibers of the blank material freely extended along the said edge to provide a velvety edge.

In one method of providing such an edge for the cups, the blanks are cut from a single sheet of paper by a male and female type of cutting die which may be dulled along that portion thereof which cuts the drinking edge of the blank so that, in the cutting operation, the material along the said edge is pulled apart, instead of being cut or sheared; thus leaving the fibres of the said material in a disrupted state and thereby forming an edge which is softer in texture than the material of the cup.

Another method whereby the said edge may be obtained, is that of loosening the fibers along the said drinking edge after the blanks have been cut by the above described present method, either before or after the cup has been formed. This may be done by means of a wire brush, or by what is called in the art, a "deckeling" process, or further, by the treatment of the said drinking edge with certain chemical, either alone or in combination with a mechanical process.

It will be clearly seen, from the illustrations in the drawing, that the said drinking edge will then be lined with a pile of loose fibers from the material of the blank so that it cannot cut the user's lips.

It is desired to have it understood that although we have described some of the methods whereby a "velvet" or soft edge may be formed for a paper drinking cup to render the said cup safe in the use thereof, other methods may be used, if desired, without departing from the scope of our invention.

We claim:

1. A drinking cup of the character described in which the material thereof is substantially softened in texture at the drinking edge of said cup.
- 5 2. A paper drinking cup having a velvety drinking edge of single thickness comprising a pile of loose fibres.
- 10 3. A drinking cup of the character described formed from a blank of sheet material and having a velvety drinking edge.
- 15 4. A paper drinking cup having a drinking edge of single thickness along which the fibers of the paper are substantially disrupted to form a pile of loose fibres.
- 15 5. A drinking cup of the character described having an unbroken free drinking edge which is substantially softer in texture than the material of said cup.
6. A paper article of the character described

having a free edge along which the fibres of the paper are purposely disrupted to provide a substantial pile of loose fibres and thereby reduce the cutting tendency of said edge.

7. A paper cup of the character described 5 formed from a blank which is first cut and then treated to change the structure of the free edge thereof to reduce the cutting tendency of the said edge which forms the drinking edge of said cup.

8. A cup formed from a blank of paper which 10 is especially treated, either during the operation of cutting the same or by a separate operation, to change the structure of the free edge of said blank to reduce the cutting tendency of the said edge thereof which forms the drinking edge of 15 said cup.
